UNITED STATES PATENT OFFICE.

EUGENE SPECHT AND LOUIS FIX, OF MILWAUKEE, WISCONSIN.

HEATING-STOVE.

SPECIFICATION forming part of Letters Patent No. 319,934, dated June 9, 1885.

Application filed February 1, 1884. (No model.)

To all whom it may concern:

Be it known that we, EUGENE SPECHT and LOUIS FIX, citizens of the United States, residing at Milwaukee, in the county of Milwaukee 5 and State of Wisconsin, have invented certain new and useful Improvements in Heating-Stoves; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The object of our invention is in a coal-burning stove to compactly and conveniently combine the characteristics both of a stove, a furnace, and ventilating apparatus, which we accomplish by providing a well-arranged combustion-chamber and ash-removing mechanism, in connection with suitably - arranged hot-air chambers and ventilating mechanism.

Referring to the drawings accompanying this specification, Figure 1 is a front view of our heating-stove. Fig. 2 is a vertical sectional view of the same on the line *xx* of Fig. 1. Fig. 3 is a view from above of a cross-section on a line of *yy* of Figs. 1 and 2. Fig. 4 is a view from below of a cross-section on a line of *zz* of Fig. 2. Fig. 5 is a side view of our heating-stove with the jacket or outer case removed. Fig. 6 is a rear view of same. Fig. 7 is a perspective view of the cold-air duct. Fig. 8 is a vertical sectional view from front to rear of that portion of our stove below the combustion-chamber. Fig. 9 is a view from above of a cross-section at the bottom of the combustion-chamber.

The magazine or combustion-chamber A has the adjustable sliding grate *a*, the rearwardly-inclined front portion, *b*, the permanently-affixed grate *c*, and extending therefrom the tubular outward passage *d*, adjustably opened or closed by the transparent door *e*, the smoke-pipe *f*, gas-pipe *g*, and usual fuel-admitting adjustable cover, *h*.

The ash-removing mechanism consists of the semicircular adjustable sliding grate *a*, supported in the horizontal grooves *i*, rigidly-attached rod-handle *j*, the chamber *k*, the opening therefrom, and door *l*, and also the opening

and gate *m* in the bottom of said chamber, the upward-projecting flange or guard *n*, and the downwardly-inclined and outwardly-opening chute *o*, said gate *m* sliding horizontally 55 in the grooves *q*, and having the rigidly-attached rod-handle *p*.

The hot-air chambers B B, inclosed by jackets B', and the ventilating mechanism in connection therewith, consist of the cold-air duct 60 C, preferably for car service, being made as a two-way duct, having the gate *r* hinged at its lower edge and adapted to swing automatically to rearward, according to direction of running of the car, and lie against the rear side of 65 the opening through the car-floor in which it swings, thereby directing cold air from below in front up into the air-chamber, the air-chamber bottom, D, having openings and adjustable sliding gates *s*, with their rigidly - attached 70 rod-handle *t*, adapted, by the opening or closing of said apertures, to regulate the amount of cold air received. The vertical partition *u*, the circular horizontal partition *v*, the upwardly-extending and spirally-curving partition-wings *w*, the chamber 2, open at the top continuously from the chamber at the rear, inside the wings *w*, and extending downwardly to and opening outwardly into and continuing as the hot-air pipe 3, which pipe 3 may run 75 80 the length of the room or car, and, being open at its outer extremity, discharges the heated air into the room or car.

The grate *a*, by its rod-handle *j* and the grooves *i*, is adapted both to be shaken from 85 side to side for sifting out the ashes, the handle *j* moving radially in the slot 4 in the outer case, and also to be withdrawn to the front from the opening in the bottom of the combustion-chamber, allowing the contents of the 90 combustion-chamber to fall through the same, the rearwardly-inclined part *b* being provided to furnish unoccupied space at the bottom in front to which to withdraw said grate, and also to carry the contents of the combustion-chamber rearwardly to said grate-opening *a*. 95

The grate *c*, tubular opening *d*, and transparent door *e* are adapted for applying a match in starting a fire in the combustion-chamber, and for obtaining the illuminating effect of the 100 glowing coals in the combustion-chamber after the fire is lighted.

The flue *g* is adapted to carry off smoke and unconsumed gases in connection with the smoke-pipe *f*.

From the chamber *k* ashes may be removed 5 either through the door *l* or through the opening *m* and chute *o*.

The arrangement of the air-chambers is such that the cold air coming in at the openings *s*, as it is heated, rises up in front of the partition- 10 wings *w*, and passes over the top of them and down at the rear into the chamber 2 and out through pipe 3, the air being thus exposed to a great extent of heating-surface, becoming thereby thoroughly warmed, and also by said 15 arrangement securing an ample supply of fresh air to the apartment or car into which the hot-air pipe 3 opens.

Having thus described our invention, what we claim as new, and desire to secure by Letters Patent, is—

In a heating-stove, the hot-air chambers *B* *B*, provided with cold-air flue *C*, having automatically-operating gate *r*, adjustable sliding gates *s*, upwardly-extending and spirally-curving partition-wings *w*, and downwardly-extending and outwardly-opening chamber 2, in combination with chamber *A*, having grated bottom *a*, and smoke-pipe *f*, adapted for combustion of fuel, all substantially as and for the purpose set forth. 25

In testimony whereof we affix our signatures in presence of two witnesses. 30

EUGENE SPECHT.
LOUIS FIX.
